US00D984549S

(12) **United States Design Patent** (10) **Patent No.:** **US D984,549 S**
Pearce (45) **Date of Patent:** **** Apr. 25, 2023**

(54) **PROJECTILE LOADER**

(71) Applicant: **KORE OUTDOOR (US), INC.**, Fort Wayne, IN (US)

(72) Inventor: **Mark Roland Pearce**, Lindenwold, NJ (US)

(73) Assignee: **KORE OUTDOOR (US), INC.**, Fort Wayne, IN (US)

(**) Term: **15 Years**

(21) Appl. No.: **29/848,686**

(22) Filed: **Aug. 4, 2022**

Related U.S. Application Data

(62) Division of application No. 29/718,908, filed on Dec. 30, 2019, now Pat. No. Des. 961,002.

(51) **LOC (14) Cl.** **21-01**

(52) **U.S. Cl.**

USPC **D21/461**; D21/573

(58) **Field of Classification Search**

USPC D21/461, 567, 570, 571, 572, 573, 274, D21/575; D22/100, 101, 103, 104, 108, D22/109

CPC F41B 11/52; F41B 11/70; F41B 11/50; F41B 11/53; F41B 11/57

See application file for complete search history.

(57) **CLAIM**

The ornamental design for a projectile loader, as shown and described.

DESCRIPTION

FIG. 1 is a rear perspective view of a projectile loader in accordance with my new design;

FIG. 2 is a front perspective view of the projectile loader as shown in FIG. 1;

FIG. 3 is top view of the projectile loader as shown in FIG. 1;

FIG. 4 is a bottom view of the projectile loader as shown in FIG. 1;

FIG. 5 is a right side view to the projectile loader shown in FIG. 1;

FIG. 6 is a left side view of the projectile loader shown in FIG. 1;

FIG. 7 is a front view of the projectile loader shown in FIG. 1;

FIG. 8 is a rear view of the projectile loader shown in FIG. 1.

The broken lines shown in the drawings depict portions of the projectile loader that form no part of the claimed design.

1 Claim, 8 Drawing Sheets
